P. E. YOUNG,
PROCESS FOR RECLAMING RUBBER AND COTTON FROM WASTE.
APPLICATION FILED SEPT. 19, 1918.
1,321,201. Patented Nov. 11, 1919.

Inventor,
Philip E. Young.

UNITED STATES PATENT OFFICE.

PHILIP E. YOUNG, OF FAIRHAVEN, MASSACHUSETTS, ASSIGNOR TO ACUSHNET PROCESS COMPANY, INC., A CORPORATION OF NEW YORK.

PROCESS FOR RECLAIMING RUBBER AND COTTON FROM WASTE.

1,321,201.

Specification of Letters Patent. Patented Nov. 11, 1919.

Application filed September 19, 1918. Serial No. 254,761.

To all whom it may concern:

Be it known that I, PHILIP E. YOUNG, of Fairhaven, Massachusetts, have made certain new and useful Improvements in Processes for Reclaiming Rubber and Cotton from Waste, of which the following is a specification.

Many efforts have been made to reclaim waste containing both cotton and rubber in such manner that both products will be obtained in forms of value. It has been pointed out in the application of Theodore F. Furness, Serial No. 163,520, filed April 20, 1917, that such a result can be obtained by disintegrating the fabric while in the presence of water and stripping the rubber from the threads and fibers resulting from such disintegration. My process relates to an improved method of disintegrating the fabric and stripping the rubber from the threads and fibers, whereby material savings in operation are had and improved products are obtained.

As an illustration of my invention I will describe it as applied to the uncured trimmings resulting from the manufacture of automobile tires that are known to the trade as "friction scrap." This waste largely consists of strips of canvas with which the rubber is very closely incorporated. The fabric in the strip is usually cut on the bias so that if the strip is about half an inch wide the threads of the fabric will not be substantially more than three-quarters of an inch long. Such a strip can very readily be unwoven into its separate threads but, if so unwoven, each thread will remain largely coated with rubber. I have discovered, however, that if such a strip is wet and subjected to a strenuous picking operation which will tear out from the strip not the threads themselves but the strands of plies of the threads, the rubber will tend to cohere into small balls and the strands that are torn loose will be stripped practically clean of rubber. It is, of course, impracticable to pick all or even substantially all of the strands out of the rubber in one operation, but by repeating the process a progressive disintegration is obtained which should be carried to the point where the cotton is sufficiently clean of rubber so that it can be handled in a standard cotton waste machine of desired type, and the rubber can be washed on a rubber wash mill.

In addition to my improved method of progressively disintegrating the fabric and stripping the rubber from the threads and fibers, my invention involves the use of novel methods of separating the rubber from the cotton.

At the time the plies or strands are torn from the sheet and stripped of rubber I permit both the rubber and the cotton to be thrown by the picking machinery with considerable force and effect a separation by the different physical qualities of the two when so thrown. For example, if the two are thrown against an inclined board, the cotton will slide down the board or, if wet enough, will stick to it, while the rubber will bounce some distance away. So if both are thrown horizontally or in an upward direction the rubber will be thrown some distance away while the cotton will drop very near the point from which it is thrown. These effects may also be aided by blowing or winnowing the cotton from the rubber. In other words I use the same force which helps in picking the cotton from the rubber, to impart motion to both, and effect a separation through their difference in mass and density.

In practising my invention I first pass the friction scrap through an ordinary cracker mill and sheet it in the presence of water, and then feed it into a picker, such as the one diagrammatically represented in the accompanying drawing. The wet sheet formed in the cracker, designated with the letter S, is put on an apron 2, from which it passes between the feed rolls 3 and 4. These rolls push the sheet at a speed of about 10 feet per minute up the surface of the feed plate 5 against which it is held by the roll 6. As the sheet emerges from between the feed plate 5 and the roll 6, it comes in contact with the teeth 7 of the cylinder 8. This cylinder rotates with a peripheral speed of from 3,000 to 5,000 feet per minute so that the teeth tear the plies or strands out of the fabric. As the cotton fibers are torn from the waste the rubber collects in small balls or particles. The cotton and rubber together are thrown by the wheel 8 against the conveyor apron 9, and the rubber, having a considerable resiliency, bounces from the conveyor 9 into a conveniently placed receptacle 10, as shown in dotted lines. The cotton, on the other hand, being wet tends to stick to the conveyor 9 and is carried over

the upper end of this conveyer, from which it drops to the floor. The fine fibers of cotton that dry so rapidly that they do not stick to the conveyer 9 are largely carried 5 over the top of this conveyer by the draft created through the rotation of the wheel 8. Separation of the lint from the air current may be accomplished by inclosing the picker in a casing 11, in one side of which is a 10 screen 12.

While the material behind the conveyer 9 will be found to be largely cotton, and the bulk of the rubber will be in the receptacle 10, it is not to be understood that one 15 pass through this picker will give a clean separation. However, if the cotton is partly dried, one or two additional passes through the machine will leave it sufficiently clean to be garnetted and carded; in like manner 20 the rubber should be resheeted and given a second pass—or more if necessary. After substantially all of the cotton is picked out of the rubber, the latter should be washed. For this purpose I have found that while 25 there is considerable difficulty in getting the rubber clean on an ordinary wash mill, very satisfactory results can be obtained by the use of the type of wash mill shown in United States Patent No. 1,267,492, of May 28, 1918. 30 To have my process operate to the best advantage it is advisable that the sheet of rubber waste, on which the picker roll operates, be wet. It also will be found that this process is far more effective on rubber waste 35 in which the rubber has a considerable degree of plasticity, such as uncured friction scrap. With other forms of waste it may be necessary, first, to subject the rubber to some well known plasticizing treatment, for 40 I find it highly desirable that the waste should be in such condition that it will sheet and not pulverize upon being ground on a mill—a condition exactly the reverse of that desired by those who heretofore have attempted to separate cotton from rubber by 45 winnowing or similar processes.

It will be readily apparent that my process can be carried out on many types of machine other than the one suggested in the 50 drawings and I do not wish to limit myself to the type of machine shown.

It is also apparent that this process can be used to separate wool or silk from rubber, if waste containing these materials is obtainable. The use of cotton is described in 55 the claims and specification for illustrative purposes only, as this is substantially the only fibrous material found to any great extent in rubber scrap.

60 What I claim is:

1. The process of separating cotton fiber

or the like from rubber waste which comprises the steps of wetting the waste, passing the waste between rollers whereby the waste is formed into a sheet, and feeding 65 such sheet gradually to a high speed picker whereby the fabric is torn from the sheet in the form of threads and fibers and the rubber is torn from the sheet in small balls or particles.

2. The process of separating cotton fiber or the like from rubber waste which comprises the steps of forming the waste into a plastic sheet, feeding the sheet gradually to a high speed picker whereby threads and 70 fibers of the cotton are progressively torn from the sheet and simultaneously stripped of rubber and the plastic rubber is torn from the sheet in small aggregates, throwing the cotton and rubber through the air before 75 opportunity is given for the material to reform into large aggregates, and separating cotton from the rubber during the movement imparted by such throwing.

3. The process of separating cotton fiber 80 or the like from rubber waste which comprises forming the waste into a moist plastic mass such that particles of rubber from the mass will tend to cohere to each other more readily than such particles will adhere to 85 fibers of the fabric and comminuting such mass by the action of a picker whereby threads and fibers of the fabric are produced substantially free from rubber, and the rubber is produced in the form of small aggregates without the formation of rubber dust. 90

4. The process of separating cotton fiber or the like from rubber waste which comprises forming the waste into a plastic sheet, feeding the sheet gradually to a picker so 100 that threads and fibers of cotton and small aggregates of the rubber are torn from the edge of the sheet, throwing the rubber and cotton through the air together, and separating cotton from the rubber by arresting 105 the motion which the cotton acquires from such throwing, more quickly than the like motion of the rubber is arrested.

5. The process of separating cotton fiber or the like from rubber waste which comprises the steps of wetting the waste, passing the waste under a roller and feeding the waste gradually to a high speed picker whereby the fabric is torn from the waste in the form of threads and fibers and the 110 rubber is torn into small particles, throwing the cotton and rubber together from the picker and separating cotton from the rubber by blowing the cotton out of its normal course.

PHILIP E. YOUNG.
